UNITED STATES PATENT OFFICE

GUSTAV JOHNSON, OF WEST ROXBURY, MASSACHUSETTS, ASSIGNOR TO UNITED-CARR FASTENER CORPORATION, OF CAMBRIDGE, MASSACHUSETTS, A CORPORATION OF MASSACHUSETTS

METHOD OF FORMING AND ATTACHING SEPARABLE FASTENER ELEMENTS

Original application filed July 14, 1928, Serial No. 292,896, now Patent No. 1,865,393, June 28, 1932.
Divided and this application filed February 2, 1929. Serial No. 337,035.

My invention aims to provide improvements in separable fastener elements and the method of forming and attaching the fastener elements to a tape or stringer.

This application is a division of my prior application, Serial No. 292,896, filed July 14, 1928 now Patent 1,865,393.

In the drawing which illustrates a preferred embodiment of my invention:—

Figure 1 is an elevational view of portions of stringers attached to a part having an opening to be closed by the fastener elements secured to the stringers and also shows a slider for fastening and unfastening the fastener elements;

Fig. 2 is an enlarged section taken on the line 2—2 of Fig. 1 showing parts in elevation and parts in cross-section;

Fig. 3 is a skeleton view showing one method of passing a tape or stringer between two molds which form and attach the fastener elements to the tape or stringer;

Fig. 4 is an enlarged section taken on the line 4—4 of Fig. 3 showing the manner in which the fasteners are molded and attached to the tape or stringer;

Fig. 5 is a section taken on the line 5—5 of Fig. 4 showing how the female fastening means is formed in the fastener element; and

Fig. 6 is a skeletonized view of a pair of discs having a number of molds spaced about their peripheries for attaching a series of fastener elements to a stringer which is shown passing between the discs.

Referring to the embodiment of my invention illustrated by the drawing, I have shown, particularly in Figure 1, two tapes or stringers 1 and 2 of flexible material, such as cloth, leather, etc., attached to an article 3 adjacent the edges of an opening in the article. The article may be a coat, tobacco pouch, overshoe, etc. Each stringer has a number of fastener elements 4 secured thereto in spaced relation for engagement to close the opening in the article 3. A slider 5 of the conventional type is also shown.

My invention is in the fastener elements 4, the method of making them and the manner of attaching them to a stringer. Therefore, I have illustrated in a general manner a par-

ticular type of fastener element and means for making and assembling the fastener elements to a stringer.

Heretofore, fasteners of the general type illustrated have been made of metal and then attached to a stringer in various ways. My invention is directed primarily to the making of the fastener elements by molding them from a substance which when compressed will retain its shape or which may be heated during the compressing operation in order to harden the substance. Any suitable substance may be used in making the fastener elements as, for instance, rubber composition, which becomes hard when pressed or vulcanized, celluloid compositions containing substances impregnated with resin, or the like, to produce a tough and hard material.

Heretofore, fasteners of the metal type were usually formed complete and thereafter attached to a stringer as a separate operation. My invention simplifies all this into a single operation whereby the fastener elements are molded and secured to the edge of a stringer at the same time, as best illustrated by Figs. 3 and 4.

One advantage of my invention is in the simple mold means by which female means, in the form of a recess 6 for engagement with the male means 7 of a cooperating fastener element, may be formed at the same time that the fastener element is formed and attached to a stringer. Therefore, I may form fastener elements in which each has a female or socket portion and a male or stud portion, as shown in the drawing, or one set of fastener elements may have two stud portions while the other set has two socket portions.

The mold blocks 8 and 9, shown in Figs. 3, 4 and 5, may be operated in any suitable manner and the moldable material may be fed into the molds in any suitable manner. Furthermore, the mold blocks 8 and 9 may be operated to move toward and away from each other or rotatable discs may be provided with a series of molds, as illustrated by Fig. 6.

In order to form the recess 6 at the same time the fastener elements are secured to a stringer, I have provided the mold block 8 with a male projection 10 which forms a re-

- cess 6 elongated at one side. In fact the recess 6 extends through one side of the fastener element, as shown in Figs. 2 and 5, so that there is no wall at one side of the recess.
- 5 The reason for one side of the recess being open is to allow the male projection 10 to come out of the recess after the fastener element has been formed and attached to a stringer.
- 10 The stringer is preferably provided with a beaded edge 11 (Figs. 2 and 4) so that the material which forms the fastener element will flow in back of the bead at each side of the stringer to lock the fastener in place as
- 15 the stringer is fed between the mold members 8 and 9. Thus, at predetermined spaced intervals along the beaded edge of the stringer, a fastener member is formed and attached thereto in a very simple and efficient manner.
- 20 While, in the particular method I have shown and described, it is necessary to extend the recess 6 through one side of the fastener element, the fact that there is no wall at one side of the recess does not interfere with the
- 25 successful operation of the fastener elements. Reference to Figs. 1 and 2 will readily disclose the fact that the fastener elements cannot be separated accidentally by side strains and stresses because the wall 12 at the other
- 30 side of the recess effectively cooperates with the male portion 7 of a cooperating fastener element to prevent such separation.

I am aware that various means may be employed to secure the result which my application is intended to cover and, therefore, I wish it to be understood that my invention is directed broadly to the idea of forming fastener elements, for the purposes illustrated and described, from any suitable plastic material which may be formed into durable fastener elements of this type. I also wish it to be understood that I have illustrated and described a simple specific form of means for carrying out the method of forming the fastener elements and the method of attaching them to a stringer. Therefore, reference is made to the following claims to indicate the scope of my invention.

I claim:

- 50 1. The method of forming and attaching multiple operative fasteners to a stringer which comprises passing a stringer between opposed mold forms, supplying moldable material to said mold forms and applying the
- 55 molded material to the edge of the stringer in the form of fasteners applied to the stringer at predetermined spaced intervals.
2. The method of forming and attaching multiple operative fasteners to a stringer which comprises passing a stringer between opposed mold forms, supplying moldable material to said mold forms and applying the
- 60 molded material to the edge of the stringer in the form of fasteners applied to the stringer at predetermined spaced intervals, and

which also comprises forming a male projection on one face of each of the stringers and a recess on the opposite face simultaneously with the forming and attaching of the fastener members.

In testimony whereof, I have signed my name to this specification.

GUSTAV JOHNSON.
